UNITED STATES PATENT OFFICE.

AARON C. FREED, OF ROYERSFORD, PENNSYLVANIA.

DESIGN FOR A CASING FOR SINK OR SEWER TRAPS.

SPECIFICATION forming part of Design No. 30,800, dated May 16, 1899.

Application filed April 21, 1899. Serial No. 713,973. Term of patent 14 years.

To all whom it may concern:

Be it known that I, AARON C. FREED, a citizen of the United States, residing at Royersford, in the county of Montgomery and State 5 of Pennsylvania, have invented and produced a new and original Design for the Casing of a Sink or Sewer Trap, of which the following is a specification.

My invention relates to a new and novel design for the casing of a sink or sewer trap; and the leading feature consists in the peculiar configuration given to the same, whereby it may be distinguished from other articles for a similar purpose now in use and where- 10 by also a neat and ornamental appearance is imparted to the same.

In the accompanying drawings, Figure 1 is a side elevation of the casing of a sink or sewer trap constructed according to my design. Fig. 2 is a plan view of the same.

In the said drawings the reference-numbers 1 and 2 designate the upper and lower sections of the casing, each consisting of a semi-spherical cup formed at the upper and lower 25 ends, respectively, with a screw-threaded boss 3 and an angular portion 4. At the meeting

edges said sections are formed with flanges 5, provided with apertured lugs 6. At one side each of said sections is formed with a curved recessed extension 6, which extensions coincide with each other and are formed with flanges which form extensions of the flanges 5 and are also formed with apertured lugs corresponding with the lugs 6. 30

From the above it will be seen that when 35 the two sections are connected together an approximately spherical-shaped casing will be produced, with curved extensions at one side and screw-threaded bosses and angular portions at each end. 40

What I claim is—

The design for the casing of a sink or sewer trap, substantially as herein shown and described.

In testimony whereof I have hereunto set 45 my hand in presence of two subscribing witnesses.

AARON C. FREED.
